UNITED STATES PATENT OFFICE.

FRED A. LONG AND NED C. LONG, OF WASHINGTON, IOWA.

WAGON-TONGUE.

No. 924,480.

Specification of Letters Patent.

Patented June 8, 1909.

Application filed October 14, 1908. Serial No. 457,677.

To all whom it may concern:

Be it known that we, FRED A. LONG and NED C. LONG, citizens of the United States, residing at Washington, in the county of Washington and State of Iowa, have invented certain new and useful Improvements in Wagon-Tongues, of which the following is a specification, reference being had therein to the accompanying drawing.

10 Our invention relates to wagon tongues, and it is particularly directed to a novel arrangement and construction that will facilitate the removal of the tongue from its appurtenances when the occasion so requires.

15 To the accomplishment of the recited object, and others coördinate therewith, the preferred embodiment of our invention resides in that construction and arrangement of parts hereinafter described, illustrated in 20 the accompanying drawings, and embraced within the scope of the appended claims.

In said drawings:—Figure I is a top plan view of the wagon tongue coupling embodying our invention. Fig. II is a bottom plan 25 view of the arrangement. Fig. III is a central longitudinal section of Fig. I. Fig. IV is a plan view in detail of the tongue extremity, and Fig. V is a top plan view of the 30 tongue coupling illustrating a modification of the hammer-strap and its appurtenances therewith.

Referring to the drawings for a detail description of our invention, the numeral 5 designates the inner terminal of the tongue proper, the proximal end of which is enlarged, as at 6, and presents a diminution of thickness from this point to its distal end, adjacent which it is rabbeted on opposite sides, as at 7 and 8. The terminal portion of 35 the tongue is arranged medially of the hounds (9), the enlargement (6) being interposed with respect to the outer ends of said hounds and secured thereto by the bolt (10), which extends through the metallic 40 plate (11) and the substantially U-shaped retaining bracket (12), the latter being fastened on the lower sides of the hounds by the coupling bolts (13), or other equivalent fastenings. The rabbeted portions (7) of 45 the tongue are designed to lie contiguous the transversely extending pivot rod (7^a). The extremital portion which is provided with a rabbet (8), as hereinbefore explained, presents what is commonly known as a tenon for 50 coöperation with the U-shaped socket (14) which is struck-up centrally of the metallic

strip (15), the latter having opposed laterally deflected terminals (16) projecting beyond the sides of said hounds to form legs adapted to engage the running gear and limit the pivotal movement of said hounds, and being attached to the cross beam (17) by the bolts (18).

In Fig. I we have shown the use of a hammer-strap comprising a semi-circular portion (19) and a lateral projection (20), the terminals of said portions and projection being fixed to the hounds (9) at 21, and the plate (11), at 22, respectively.

In Fig. V of the accompanying drawings 70 we have illustrated a slight modification of the hammer-strap, the same having the general conformation of a T and being fastened, to the cross beam and plate (11) by the bolts (23) and bolt (10), respectively. 75

From the foregoing description it will be perceived that the tongue (5) may be readily detached from the hounds (9) by withdrawing the bolt (10) and thereby obviating the necessity of removing a tongue and all 80 of its appurtenances as an entirety as has heretofore been the case.

Manifestly, the means we have devised will be of considerable advantage in cold and inclement weather as if the vehicle is in the 85 open the tongue may be removed and thus preserved in any convenient dry place free from the destructive elements of the weather. Furthermore, this detachable feature would be of marked assistance in unloading operations especially when the latter are confined to a minimum space.

The invention is simple in construction and operation and consequently may be manufactured at a sufficiently low cost to 95 permit of its adoption generally.

Having thus described the invention what is claimed as new is:—

1. In a device of the class specified, the combination of a pair of hounds the forward 100 ends of which are connected by a plate, a cross beam connecting the opposite ends of said hounds, and having on one side a recess disposed above the plane of said plate, a metallic strip disposed longitudinally of 105 said cross beam having a struck-out U-shaped portion overlying said recess, a tongue disposed intermediate said hounds and having a reduced extremity which is designed to enter the opening formed by said 110 recess and U-shaped portion of said metallic strip, and a substantially T-shaped hammer

strap having one limb connected to said plate and its other limb to said cross bar.

2. In a device of the character specified, the combination of a pair of tongue hounds, 5 a cross beam connecting said hounds and having a recess arranged medially on one side thereof, a transversely extending pivot rod combined with said hounds, a metallic strip secured longitudinally of said cross beam having a central U-shaped portion overlying said recess, and its opposite ends 10 projecting laterally beyond the sides of said hounds forming legs to engage the running gear and limit the pivotal movement of the

said hounds, a tongue disposed intermediate 15 the said hounds and having a reduced extremity to enter the opening formed by the recess and U-shaped portion of the metallic strip.

In testimony whereof we hereunto affix 20 our signatures in presence of two witnesses.

FRED A. LONG.
NED C. LONG.
